UNITED STATES PATENT OFFICE.

DANIEL L. CHANDLER, OF AYER, MASSACHUSETTS, ASSIGNOR TO FITCHBURG BOBBIN CLEANING MACHINE CO., OF FITCHBURG, MASSACHUSETTS, A CORPORATION OF MASSACHUSETTS.

BOBBIN-TENDER.

1,229,228.

Specification of Letters Patent. Patented June 12, 1917.

Application filed July 25, 1916. Serial No. 111,239.

To all whom it may concern:

Be it known that I, DANIEL L. CHANDLER, a citizen of the United States, residing at Ayer, in the county of Middlesex and State 5 of Massachusetts, have invented a new and useful Bobbin-Tender, of which the following is a specification.

This invention relates to a machine for automatically supplying bobbins to a bob- 10 bin stripping machine or the like.

The principal objects of the invention are to provide a device on which bobbins can be dumped indiscriminately and which will take them in proper manner and cause them 15 to be fed toward the bobbin stripper all in the same direction and at regular intervals and applied thereto; also to provide a novel arrangement of belting for supporting and feeding the bobbins, a simple and practical 20 device for turning end for end the bobbins which are presented in the wrong direction; to provide a timing mechanism for insuring the feeding of the bobbins in time with the operation of the bobbin stripping machine 25 itself; and to provide improvements in details of construction and in other features of the machine.

Reference is to be had to the accompanying drawings, in which—

30 Figure 1 is a plan of a machine constructed in accordance with this invention;

Fig. 2 is a side view of the same;

Fig. 3 is an end view;

35 Fig. 4 is a side view on enlarged scale showing the operation of reversing the bobbins that are presented in the wrong position, showing the parts in section on the line 4—4 of Fig. 1;

Fig. 5 is an end view of the tripping 40 mechanism for timing the feed of the bobbin stripper, on line 5—5 in Fig. 1;

Fig. 6 is a sectional view on the line 6—6 of Fig. 1, and

45 Fig. 7 is a sectional view on the line 7—7 of Fig. 1.

Although the principles involved in this machine are capable of application in connection with other machines, yet I have shown it herewith as adapted to feed bobbins to a bobbin stripping machine of the general type shown in several of my prior 50 patents and particularly in Patent No. 1,147,678 patented July 20, 1915. In that

machine there is a wheel A provided with radial pins B for receiving the bobbins. It 55 is for the purpose of presenting the bobbins to these pins and applying them thereto that this machine is designed.

The embodiment of the invention shown in these drawings comprises a machine having a frame 10 located adjacent to the wheel A and is provided with a power shaft 11 receiving power from a pulley 12 or from any other desired source. By means of pulleys 13 and a belt 14 power is transmitted to a 60 second shaft 15 parallel with the first and located near the bobbin stripper end. On this shaft are located a pair of drums 16 which receive two parallel wide feeding belts 17. These belts also pass over a similar pair of drums 18 on a shaft 19 at the other end of the machine. The top strands of these two belts constitute the main portion of the receiving part of the machine. They are wide enough so that they are 65 adapted to receive a basket of bobbins on them and attend to the first part of the feeding operation. They run back away from the bobbin stripper in the direction indicated by the arrows so as to carry the bobbins that are received by them back toward the rear of the machine.

The shaft 11 also drives by means of bevel gearing 20 and 21 two inclined shafts 22. Each of these shafts is provided with a 85 pulley 23. These pulleys come substantially together at their upper edges and are located at an inclination so that the belts 24 with which they are provided form a V-shaped trough for receiving bobbins. This 90 trough is so located at its discharge end that a bobbin located on it will be moved by it on a pin B of the wheel A when the pin is horizontal. These belts are located between the edges of the belts 17 and it will 95 be observed that the two pairs of belts are so inclined that the upper strands of the belts 17 are below the upper strands of the belts 24 at the end toward the bobbin stripper, and above them at the other end of the 100 machine. These belts 24 pass over pulleys 25 at the other end of the machine and idlers 26 are provided for guiding the idle strand. The clearance between the edges of these belts is made as small as convenient so that 105 they will not interfere with each other and

yet bobbins cannot pass between them. The four upper strands of the belts 17 and 24 constitute the surface on which the bobbins are dumped.

5 On one of the shafts 22 is located a crank 28 provided with a rod 29 which is connected to a shuffler driving arm 30 pivoted on a central vertical stud 31 on the frame. On this stud and fixedly connected with the arm 30 is a V-shaped oscillating shuffler 32 arranged to extend over the surfaces of the two belts 17 and adapted to be oscillated as indicated by the full and dotted lines in Fig. 1 by the action of the crank 28.

10 15 It will be understood that the bobbins are intended to be fed by the belts 24 being held in the V-shaped trough formed by them and applied to the pins B by the motion of these belts forward.

20 25 Located along the path of travel of the bobbins are two trips 35. Each one is mounted on a cross bar 36 and provided with a long spring 37 and a short spring 38 carried by headed pins to permit the trips to yield and tilt upwardly. The purpose of these as will be seen from reference to Fig. 4 is to turn a bobbin end for end if it starts to move along past these trips wrong end up. The operation is very simple as the trip engages the grooves on the large end of the bobbin and tips it over about that end as a center. If the bobbin passes through in the other direction it will be engaged by the trips in the same way, but it cannot be tipped over because the center about which it would have to turn is at the other extreme end of the bobbin. Therefore the trip has to yield.

30 35 40 For the purpose of timing the application of the bobbins to the pins B the following mechanism is shown:—The wheel A is provided with lugs 40 one for each pin. On a longitudinal shaft 41 is fixed an arm 42 located in position to be engaged and oscillated by each lug 40 as it moves above it. A spring 43 normally holds the shaft in such a position as to keep the arm 42 so placed as to be engaged by the next lug. A stop 44 is shown for limiting the position in this direction. On this shaft 41 is fixed an arm 45 which, of course, moves with the lug 40. On the shaft 41 there is fixed one of the timing stops 46.

45 50 55 The arm 45 is connected by a link 47 with an arm 48 on a parallel shaft 49. This shaft is provided with another arm 50 fixed to it and moving with the arm 48. On this is pivoted a second timing stop 51. Fixed on the arm 50 is an arm 52 which is provided with a stop pin 53 for the end of the stop 51. This arm 52 is provided with a spring 54 by which the upper end of the timing stop 51 is held up against the pin 53 normally.

60 65 The operation of the device is as follows:—The wheel A being operated inter-

mittently and the belts constantly, bobbins are dumped on the belts at any convenient point in an indiscriminate manner. Some of the bobbins will lie in the trough formed by the belts 24 and will be fed directly toward the wheel A. Those that are received by the belts 17 are fed in the opposite direction and are fed upwardly to a point above the upper edges of the belts 24 at the rear end of the machine. The operation of the crank 28 constantly oscillates the shuffler 32 which, aided by the motion of the belts 17, gradually forces these bobbins over into the trough at the center. If the bobbins pile up in the trough formed by the belts 24 the top ones will be caused to roll off on the side belts 17 near the rear end of the machine and go through the feeding operation again without causing any damage.

70 75 80 85 90 95 Bobbins which are arranged with their butt ends foremost pass under the yielding trips 35 without any material disturbance and the others are turned over end for end. The reason for using two trips is that if the first one fails to work the second one will be practically sure to perform the desired operation.

100 105 110 115 120 125 When the bobbins come to the timing stops they will be stopped by one or the other of them because one is always down, and in Figs. 1 and 2 a bobbin is shown stopped by the second one 46. Just before each pin B is brought to horizontal position ready to receive a bobbin one of the lugs 40 lifts the arm 42 and oscillates the shaft 41 so as to lift the timing stop 46 so as to let the bobbin indicated in these figures pass along. At the same time the arm 45 is moving down to the dotted line position shown in Fig. 6 and the shaft 49 turned so as to bring the arm 50 down to the dotted line position shown in Fig. 7. This moves the other timing stop 51 down into a position to engage the head of the next bobbin and prevent its being fed forward until the lug passes the arm 42. Then the parts are restored to the first position and the next bobbin is free to pass under the timing stop 51 and into contact with the lowered timing stop 46 to await its turn.

130 In this way it will be seen that the machine takes care of the bobbins and insures their being fed forward properly. No attendant is required for it and a bobbin boy can supply bobbins to several of these machines without trouble.

135 Although I have illustrated and described only a single form of the invention and shown it as applied to a bobbin stripping machine of only one type I am aware of the fact that modifications can be made in the machine and that it can be applied to other bobbin stripping machines than the one shown without departing from the scope of the invention as expressed in the claims.

Therefore I do not wish to be limited in these respects, but what I do claim is:—

1. In a machine for feeding bobbins to a bobbin stripper, the combination of two belts running substantially edge to edge in opposite directions, one of them being below and adapted to receive the bobbins directly from, the other, and an oscillating shuffer for moving the bobbins from one to the other. 5
2. In a machine for feeding bobbins to a bobbin stripper, the combination of a pair of belts running in the same direction and spaced apart, and a second pair of belts located between them and located at an angle to each other to form a trough for receiving bobbins and running in the opposite direction. 15
3. In a machine of the character described, the combination of a pair of belts running in the same direction and spaced apart, a second pair of belts located between them and located at an angle to each other to form a trough for receiving bobbins and running in the opposite direction, the first named pair of belts being located above the second pair at the end toward which the first pair of belts are running and below them at the other end, whereby they can transfer bobbins to the central pair of belts. 20
4. In a machine of the character described, the combination of a belt, a second belt located adjacent thereto for receiving bobbins and running in the opposite direction, the first named belt being located above the second one at the end toward which the first belt is running and below it at the other end, whereby it can transfer bobbins to the second belt, and movable means at the high point of the first belt for moving the bobbins on the surface thereof toward the second belt. 35
5. In a machine of the character described, the combination of a pair of wide belts forming a surface for the reception of bobbins, said belts being spaced apart, a pair of feeding belts located between them running in the opposite direction and arranged to form a trough for receiving bobbins, and means whereby bobbins placed on the first named belts will be transferred into the trough and fed thereby in the opposite direction. 45
6. In a machine for feeding bobbins, the combination of a moving member on which the bobbins are adapted to be placed indiscriminately, a pair of belts located in such a position with respect to each other as to form a trough for receiving bobbins therein and feeding them forward, and oscillating means for moving the bobbins on the surface of said moving member into said trough. 55
7. In a machine of the character described, the combination of two pairs of belts, an outside pair and an inner pair located at an angle to each other to form a trough, a vibrating member located over the discharge ends of the outer pair of belts, and means for vibrating said member to assist in moving bobbins on said belts toward the center of the machine and into the trough. 70
8. In a machine of the character described, the combination of a conveyer for conveying bobbins longitudinally, means for turning the bobbins so that they will all be presented with their butt ends foremost, and a timing stop for controlling the discharge of the bobbins from the conveyer. 75
9. In a machine for feeding bobbins, the combination of a device for conveying the bobbins along longitudinally with respect to the bobbins, a trip extending down from above and in the path of the bobbins and into position to engage the enlarged butt end of a bobbin, a couple of headed pins having springs under their heads engaging the top of said trip to hold it down yieldingly, whereby if a bobbin passes with its butt end foremost the trip will yield and perform no other function, but if the bobbin comes under the trip with its butt end in the rear the trip will engage said butt end and tip the bobbin over. 80
10. In a machine of the character described, the combination of a conveyer for bobbins, a pair of timing stops located in position to move into the path of the bobbins, a shaft on which the first stop is fixed, an arm on said shaft, means for periodically oscillating said arm so as to raise the stop on that shaft, a second shaft connected with the first shaft for turning the second shaft when the first stop is raised, the second stop being pivotally connected with the second shaft and arranged to be lowered thereby when the first stop is raised. 85
11. The combination with a bobbin stripper having a rotary wheel and provided with radial pins for receiving the bobbins, of a non-positive feeding device for carrying the bobbins toward said pins, a time stop located in the path of said bobbins, and means controlled by said wheel for moving said time stop into and out of the path of the bobbins in synchronism with the operation of the wheel. 90
12. The combination with a bobbin stripper having movable pins for entering and holding the bobbins, of means for feeding bobbins thereto comprising a moving member for receiving the bobbins indiscriminately, means for receiving the bobbins from said member and feeding them toward the bobbin stripper in alinement with one position of said pins, and means controlled by the bobbin stripper for timing the feed of the bobbins thereto to cause a bobbin to be fed when a pin is in said position. 105
13. The combination with a bobbin strip- 130

ping machine comprising a rotary member provided with bobbin receiving pins projecting therefrom, of a pair of belts having their carrying strands located at an angle 5 to each other to form a trough for receiving and carrying the bobbins toward said member, said trough being arranged in such position that a bobbin resting therein will be fed thereby centrally with respect to one 10 of the pins of said stripper and to be received by said pin.

14. The combination with a bobbin stripping machine having movable pins for entering and holding the bobbins, of means 15 for feeding bobbins and applying them thereto, and means controlled by the bobbin stripping machine for holding the bobbins on the feeding means, and allowing them to move forward one at a time when a 20 pin of the bobbin stripping machine is in alinement with said feeding means.

15. The combination with a bobbin stripping machine having movable pins for entering and holding the bobbins, of means for taking bobbins from a mass arranged 25 indiscriminately, arranging them in alinement and feeding them forward to said machine in alinement with one of said pins.

16. The combination with a bobbin stripping machine having movable pins for entering and holding the bobbins, of means for taking bobbins from a mass arranged indiscriminately, arranging them in alinement with said pins, turning some of them 30 over so as to locate them all with their butt ends foremost, and feeding them forward 35 and on said pins.

In testimony whereof I have hereunto affixed my signature.

DANIEL L. CHANDLER.
